US0D1073329S

(12) **United States Design Patent** (10) **Patent No.:** **US D1,073,329 S**
(45) **Date of Patent:** **** May 6, 2025**

(54) **MIRROR**

(71) Applicant: **Dongguan Powerme Tech. Co., Ltd,**
Dongguan (CN)

CN 306500522 * 4/2021
CN 308384172 * 12/2023

(72) Inventor: **Guowei Yang**, Dongguan (CN)

(**) Term: **15 Years**

(21) Appl. No.: **29/987,698**

(22) Filed: **Jan. 26, 2025**

(51) LOC (15) Cl. **06-07**

(52) U.S. Cl.

USPC **D6/309**; D6/308; D6/310

(58) **Field of Classification Search**

USPC D6/300, 308–310, 312; D26/38;
D28/64.1–64.7

CPC A45D 42/00; A45D 42/10; A47G 1/04

See application file for complete search history.

(57) **CLAIM**

The ornamental design for a mirror as shown and described.

DESCRIPTION

FIG. 1 is a perspective view of a mirror showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mirror shown in an alternate configuration; and,

FIG. 10 is a perspective view of the mirror shown in an alternate configuration.

The dash-dash broken lines in the drawings depict portions of the mirror that form no part of the claimed design.

1 Claim, 10 Drawing Sheets
